COTTON-REGINNING MACHINE.

1,215,741.

Specification of Letters Patent.

Patented Feb. 13, 1917.

Application filed July 30, 1912. Serial No. 712,253.

To all whom it may concern:

Be it known that I, LOUIS K. STEPHENS, a citizen of the United States, residing at 1730 Fourth avenue, Dallas, in the county 5 of Dallas and State of Texas, have invented certain new and useful Improvements in Cotton-Reginning Machines, of which the following is a specification.

My invention relates to a new and useful 10 cotton reginning machine, and its object is to provide a machine, by which dirty or matted ginned cotton may be much improved in grade, by subjecting the same to a mechanical process, by which the fibers 15 will be separated from each other, reducing the cotton to a loose fluffy mass, and at the same time removing dirt or other foreign substances from the same.

Another object is to provide a novel 20 mechanism for reducing the cotton to a loose fluffy mass, which mechanism comprises a gin saw cylinder and a brush cylinder mounted in the usual co-operative relation, and a pair of saw cylinders of comparatively small diameter mounted above the gin saw cylinder and spaced horizontally from each other, cotton being fed between the small cylinders to the gin saw cylinder, and the small cylinders being subjected to a longitudinal reciprocating motion during the feeding process.

Finally, the object of the invention is to provide a device of the character described, that will be strong, durable, simple, and 35 efficient, and comparatively easy to construct, and also one that will not be likely to get out of working order.

With these and various other objects in view, my invention has relation to certain 40 novel features of the construction and operation, an example of which is described in the following specification, and illustrated in the accompanying drawings, wherein:

Figure 1 is an end view of a cotton reginning machine, in which are embodied the 45 novel features constituting the present invention.

Fig. 2 is a detail view showing a fragmentary portion of the same end of the machine illustrated in Fig. 1, this view serving to make clear a certain transmission mechanism which is partially hidden by other parts in Fig. 1.

Fig. 3 is another detail view, in which is 55 shown an upper portion of the end of the

machine illustrated in Fig. 1, said portion being partially concealed by overlying parts in Fig. 1.

Fig. 4 is a view showing the machine partly in front elevation and partly in longitudinal vertical section, the section being taken upon the line W—W of Fig. 1.

Fig. 5 is a transverse vertical sectional view, taken upon the line X—X of Fig. 4.

Figs. 6 and 7 are respectively a top and 65 end view of a reciprocating frame which constitutes a feature of the invention.

Fig. 8 is a detail sectional view showing the mounting of two shafts in one of the end frames of the machine, the section being taken upon the line Y—Y of Fig. 1.

Fig. 9 is a detail view of an eccentric and eccentric rod by which a reciprocating motion may be communicated to the frame detailed in Figs. 6 and 7.

Fig. 10 is a detail view of a vertically adjustable bearing adapted to carry the extremities of two shafts mounted at right angles to each other.

Fig. 11 is a detail sectional view of a pair 80 of bevel gears establishing a communication of rotation between two shafts, the section being taken upon the line Z—Z of Fig. 8.

Referring now more particularly to the drawings, wherein like reference characters 85 designate similar parts in all the figures, the numeral 1 denotes two oppositely disposed frame members, one of which supports each extremity of the machine. Each frame member is provided with a pair of legs 2 90 having their feet bolted or otherwise secured to the extremities of two beams 3, extending longitudinally of the machine beneath the same. The upper portions of the frame members 1 are furthermore rigidly connected by three elongated beams 4, parallel to the beams 3. The frame members 1 and 2 respectively support the extremities of two parallel shafts 5 and 6, said extremities being each mounted in a bearing 7, pivoted between a pair of brackets 8 projecting outwardly from the correlated member 1. The frame members are each provided with two opposite slots 9 projecting toward each other from the lateral edges of the containing 95 member, and the extremities of the shafts 5 and 6 are made to pass through the inner ends of the slots 9. By employing this construction, it is made possible to remove either shaft with such parts as it carries be-

tween the frame members 1, by withdrawing the shaft laterally from its operative position in the machine. The shaft 5 carries a plurality of gin saws 10, spaced from each other in the usual manner, said saws in conjunction forming a saw cylinder, extending substantially the entire length of the machine. The shaft 6 carries a brush cylinder 11, such as forms a feature of all gins, 5 the bristles carried by said cylinder being made to contact with the teeth of the saws 10 in the usual well known manner. The two shafts 5 and 6 are made to project at one end of the machine some distance beyond their correlated bearings, and upon the shaft extremities thus projecting, there are mounted two driving pulleys 12, to which rotation may be communicated from any suitable source of motive power. The 10 direction of the rotation communicated to each shaft is indicated by the arrows in Fig. 5.

Beneath the cylinder formed by the saws 10 and slightly spaced from the same, there is mounted a semi-cylindrical screen 13, the extremities of which are mounted upon suitably curved bars of angle iron 14. The outermost extremity of each bar 14 is pivotally mounted upon the correlated frame member 1, as is indicated by the numeral 15. The innermost extremities of the two bars rest upon the ends of an elongated pipe 16, carried by a rod 17 passing through said pipe, the extremities of said rod being respectively mounted in the members 1 adjacent to the lower edges of the same. Beneath the brush cylinder 11, there is mounted a semi-cylindrical casing 18, supported similarly to the screen 13, the ends of said casing being mounted upon suitably curved angle bars 14, each pivoted at its outer end as indicated at 15, and having its inner end resting upon one of the extremities of the pipe 16.

45 A short space above the cylinder comprised by the saws 10, there are mounted two horizontally spaced saw cylinders 19, which have a diameter considerably less than that of the saws 10. The teeth of the 50 saws comprising the two cylinders 19 are pointed oppositely as is clearly shown in Fig. 5 of the drawings, and the directions of the rotations which are impressed upon the two cylinders by a mechanism hereinafter described are also opposite, as is indicated by the arrows in Fig. 5. The saw cylinders 19 are respectively mounted upon shafts 20 and 20^a, the extremities of which shafts are journaled in bearings 21, two of which bearings 55 are mounted contiguous with the outer surface of each frame member 1, between a pair of horizontal ribs 22, projecting perpendicularly from the correlated member 1. The shaft 20 is adapted to undergo a slight 60 adjustment to or from the shaft 20^a, and in

order to permit of such adjustment, the members 1 are respectively provided with horizontal slots 23 through which the extremities of the shaft 20 project. This lateral adjustment of the shaft 20 is effected 70 through a corresponding displacement of the bearings 21, supporting the extremities of said shaft. The adjustability is secured through mounting a rod 24 beneath each adjacent pair of bearings 21, said rod being 75 slightly spaced from the outer surface of the correlated member 1, and slidably mounted in bearings or brackets 25 integrally projecting from said member. Each rod 24 carries at one end an upwardly projecting arm 26, contacting at its upper portion with the rear surface of the correlated adjustable bearing. At the other or front extremity of the rod 24, there is mounted a nut 26^a, bearing against one of the brackets 80 25, the rod extremity being screw-threaded to receive said nut. Between the two brackets 25 supporting each rod 24, a coiled spring 27 is mounted upon said rod, tending to normally hold the same displaced to its forward limiting position of adjustment, and consequently exerting a corresponding effect upon the parts 20 and 19. The mechanism for communicating rotation to the two saw cylinders 19 will hereinafter be fully 85 explained.

Upon each frame member 1, there is surmounted an upper frame member substantially triangular in form, and comprising three side pieces 28, 29, and 30, integrally connected, the piece last specified being horizontal, and the other two being inclined convergently downward from the extremities of the piece 30. A pair of legs 31 support each of the members formed by the parts 28, 29, and 30, the feet of said legs being rigidly secured to the correlated members 1. The central aperture inclosed by the parts 28, 29, and 30 is in each case closed by a sheet of galvanized iron 31^a or by some other suitable material.

The upper portions of the two triangular frame members respectively support the extremities of two parallel horizontal shafts 32, vertical slots 32^a being provided at the junctures of the top piece 30 with the side pieces 28 and 29, through which slots, the shaft extremities are passed. The bearings 33, which support said shaft extremities, are spaced slightly from the outer surfaces of the members 1, and are carried at the lower ends of screw threaded rods 34, the upper ends of said rods being passed through ribs 35 one of which projects outwardly from the upper edge of each triangular member. A wing nut 35^a mounted upon each rod 34 above the correlated rib 35 supports the rod and the attached bearing, and permits said supported parts to be vertically adjusted. The slots 32^a are sufficiently elongated in a 120 125 130

vertical direction to permit the necessary amount of vertical adjustment of the two shafts 32. The lower portions of the two triangular frames respectively support the 5 extremities of two parallel horizontal shafts 36, said extremities being passed through apertures respectively provided at the lower extremities of the parts 28 and 29. The aperture provided at the lower end of each 10 member 28 will have the nature of a horizontal slot as indicated at 36^a, thus permitting the shaft 36 which passes through the slots 36^a to be adjusted to or from the other shaft 36. The stationary shaft 36 has one 15 of its extremities provided with a bearing 37 carried by the upper end of a bracket 37^a projecting integrally upward from a bar 37^b, mounted transversely of the machine, and having its extremities secured to a pair of 20 brackets 38 projecting integrally from the uppermost rib 22. The other extremity of the stationary shaft 36 may be provided with a bearing aperture in the correlated triangular frame member. Each extremity of the 25 adjustable shaft 36 is provided with a bearing 38^a, integrally mounted upon the lower extremity of a bar 39^b of T-shaped cross-section, said bar being contiguous and parallel with the member 28 of the correlated triangular frame member, and being pivoted as 30 indicated at 39^a upon the upper portion of said member 28. In order to effect a horizontal displacement of the bearings 38^a, each of said bearings is given a rigid connection with a rearwardly extending horizontal rod 39, slidably mounted in lugs 40 projecting integrally from the correlated triangular frame. Each of the rods 39 carries a collar 40^a normally contiguous with the 35 correlated lug 40 nearest adjacent to the correlated bearing 38^a. A coiled spring 40^b is interposed between the other lug 40 and the collar 40^a, said spring serving to normally hold the correlated bearing 38^a in its forward limiting position of adjustment. It 40 will thus be seen that the adjustable shaft 36 if subjected to a force sufficient to overcome the two springs 40^b, will be free to undergo a limited amount of displacement rearwardly or from the stationary shaft 36, the 45 bars 39^b at the same time being swung rearwardly about their pivoted upper ends.

Upon each of the shafts 32 and 36, there are mounted three sprocket wheels 41, one of 50 said wheels being disposed at the center of each shaft and the other two respectively adjacent to the triangular frame members. The sprocket wheels carried by the shafts 32 extending between the upper ends of the 55 members 28 and 29 form pairs with the sprocket wheels carried by the shafts 36 extending between the lower ends of said members, each of the six pairs of wheels thus formed being made to carry a sprocket 60 chain 42. Each set of three horizontally

aligned sprocket chains 42 carries a plurality of horizontal slats 43 forming an endless apron, said slats being bolted or otherwise secured to laterally projecting lugs 44 carried by the links forming the sprocket chains. The direction of travel impressed upon the two aprons during the operation of the machine is indicated by the arrows in Fig. 5. The mechanism by which this travel is maintained will now be described. Upon an extremity of one of the shafts 32, there is mounted a drive pulley 45 to which the rotation indicated by the arrow in Fig. 5 may be communicated from any suitable source of motive power. Upon the other extremity 70 of said shaft, and upon the corresponding extremity of the other shaft 32, two bevel gears 46 are respectively mounted. Each of the gears 46 engages a smaller bevel gear 47, the two gears 47 being mounted fast upon a 80 horizontal shaft 48, which has its extremities journaled in bearings 49, one of which is integral with each of the bearings 33 adjacent to the extremities of the shaft 48. It will thus be seen that the intermeshed gears 85 46 and 47 and the shaft 48 together serve to establish a communication of rotation between the two shafts 32, said shafts being caused to rotate oppositely and thereby produce a downward travel of the opposite 90 performing faces of the two aprons.

A description will now be given of a train of gearing adapted to communicate rotation from the non-adjustable shaft 36 to the two saw cylinders 19. Between the 100 bracket 37^a and the adjacent triangular frame member, a pinion 50 is mounted upon the non-adjustable shaft 36, which pinion intermeshes with a gear 51 mounted upon a stud shaft 52 carried by the lower portion of 105 the bracket 37^a. The gear 51 through engagement with a pinion 53, carried by the non-adjustable shaft 20^a, is adapted to communicate a rotation to said shaft such as is indicated by the arrow in Fig. 2. The shaft 110 52 carries the forward extremity of a swinging link 54, which has its rear extremity pivotally connected with the upper end of a swinging link 55 carried at its lower end by the shaft 20. At the juncture of the two 115 swinging links 54 and 55, a gear 56 is mounted, which gear has engagement with the gear 51 and also engages a pinion 57 mounted upon the adjacent extremity of the shaft 20, communicating to said shaft a 120 rotation such as is indicated by the arrow in Fig. 2. The purpose of establishing the swinging linkage formed by the bars 54 and 55 is hereinafter made clear.

A description will now be given of a certain mechanism by which a reciprocating motion is communicated to the two shafts 20 and 20^a in unison. Each of the triangular frame members is provided with two rearwardly projecting spaced brackets 58, 130

said brackets being integral with the upper extremity of the members 28. Between each pair of brackets 58 a pivoted bearing 59 is mounted, the two bearings 59 being horizontally aligned. Within the bearings 59 are journaled the extremities of a shaft 60 adapted to be driven by a pulley 61 carried at one extremity of said shaft, the direction of rotation being indicated by the arrow 10 in Fig. 5. At its other extremity, said shaft is made to carry a pulley 62, which pulley is adapted to communicate rotation through a downwardly extending quarter turned belt 63 to a pulley 64 mounted fast upon a shaft 15 65 transverse with the machine, and adjacent to the upper portion of the member 1 shown in Fig. 1. The shaft 65 is provided with three bearings 66, one receiving each extremity of said shaft and the other supporting the center portion of the same. Each bearing 66 is pivoted between a pair of vertically aligned bracket members 67 projecting horizontally from the correlated member 1. The shaft 65 carries two eccentrics 68 each operating a substantially 20 horizontal eccentric rod 69 extending longitudinally of the machine and passing through both frame members 1, vertically elongated slots 70 being provided in said 25 frame members to accommodate said eccentric rods. The free extremities of the two rods 69 are connected by a cross bar 71, to which bar are also secured the corresponding extremities of the two shafts 20 and 20^a, the two shafts being so connected as to offer no impediment to rotation of the same. A horizontal slot 72 is provided in the bar 71 to receive the extremity of the shaft 20 so as to permit said shaft to undergo 30 the necessary lateral adjustment.

It will thus be seen that the eccentric rods 69 and the cross bar 71 together form a longitudinally reciprocating frame engaging the two shafts 20 and 20^a, and communicating a reciprocating motion to said shaft without interfering with the rotation thereof. It is to be observed that the two pinions 58 and 57 respectively carried by the shafts 20^a and 20 are loosely keyed 45 upon said shaft to permit the latter to reciprocate without communicating the reciprocating motion to said pinions.

The operation of the above described machine will now be fully discussed, and the 55 functions of the various parts will be fully explained. The hopper formed between the two endless aprons carried by the chains 42 is intended to receive a constantly replenished supply of lint cotton, which due to 60 dirt, moisture or some other cause has been lowered in grade. The gradual downward travel of the hoppers forming faces of the two aprons causes the cotton to be gradually discharged between the adjacent lower 65 extremities of said aprons. Since the lon-

gitudinal opening between the lower extremities of said aprons is vertically aligned with the longitudinal opening between the saw cylinders 19, the cotton will be caught by the serrations of said cylinders and will be carried between the same. The saw cylinders 19 simultaneously undergo a uniform reciprocating motion and a gradual rotating motion, as has been previously explained. The gin saw cylinder 10 rotates at 75 a comparatively high rate of speed, and draws the lint from between the cylinders 19 in small particles. Owing to the reciprocating motion of the cylinders 19, a quantity of cotton passing between the cylinders 80 19 at a certain point will not all be received by a few of the saws 10, but will be distributed over a considerable number of the saws 10 according to the reciprocating stroke of the cylinders 19. An important 85 advantage is thus derived for the reason that a small quantity of cotton having a very low grade due to dirt or to any other cause, will not, after having been disintegrated by the gin saws 10, be delivered to 90 one certain portion of the brush 11 so as to cause the low grade mass of cotton to remain substantially a unit after treatment by the machine. The particles or fibers of the low grade mass will be distributed longitudinally of the saw cylinder 10 due to the reciprocating motion of the saw cylinders 19 and the low grade fibers will be so intermingled with a better grade of cotton as to materially improve the quality 95 of the whole. Another important matter incident to this construction and arrangement of parts is that the cotton, being initially placed in an elongated upwardly extending hopper having a discharge passage at its bottom, is allowed to settle down therein gradually under the action of gravity with a tendency to dispose itself in such way that a mass is formed which is approximately uniform throughout in 100 density. The flat converging aprons which form the side walls are assisted in producing a uniform bat. The aprons gradually increase the pressure on the mass which settles under gravity and force through the 105 lower throatway a comparatively compacted uniform bat, the components of which may be, and generally are, relatively small pieces of lint. They are compressed, however, into a self-sustaining bat which is fed downward 110 directly toward the main saw cylinder. The intermediate cylinders or rollers are considerably smaller in diameter than are the apron rollers, and, consequently, the transverse plane through the bat where they exert 115 their pressure can be brought close to the teeth of the saw cylinder, and the bat is held under compression at its forward edge until the fibers are caught by the saw teeth. The grip upon the bat mass is intensified by 120 125 130

the teeth on the cylinders 19; and, as a result of the structural features of these small cylinders, the teeth of the saws at 10 are enabled to pick each lint fiber away from its neighbors and effect a thorough separation of the fibers from foreign materials, such as sand, grit, or similar bodies. The two small cylinders are relatively close together, the space between them being considerably narrower than that between the aprons at their discharge throat, and, consequently, the small cylinders still further compress the bat after the initial compression has been effected by gravity and the action of the aprons.

As above noted, the saw cylinder is rotated at a high speed. The small cylinders or rolls 19, however, rotate at a relatively slow speed, and, being light, can have reciprocatory movements in directions which are longitudinal of the axis of the saw cylinder, without interference from their inertia. The bat is, as an entirety, moved laterally and axially of the cylinder by these intermediate cylinders or rollers. The short pieces of fiber or lint which may project toward the saw cylinder in planes between one saw and the next are bodily moved from one saw to another by the reciprocating movements of the small cylinders, so that there is an assurance that they will be caught by one set of teeth, or an adjacent set, and picked away from the mass at the forward edge of the bat; the purpose being to separate each fiber from its neighbors in the bat to the greatest extent possible. As the fibers are being subjected to a rapid rotation by the gin saws 10, the dirt, dust and other foreign matters will be thrown through the screen 13, due to centrifugal force, thereby separating the same from any fibers that may also be thrown from the saw. The greater portion of the fibers will adhere to the saws and will be thus transmitted to the brush 11, and any of the fibers which may be thrown against the screen 13 will quickly be again taken up by the saws and transmitted to the brush. The mechanical process carried out by the machine will be completed when the fibers are taken up by the brush 11, and the means employed to remove the fibers from said brush may be of any common and well known form, as for example a current of air. Since the use of the screen 13 presents a possibility for some of the cotton fibers to pass through said screen along with the dirt and foreign matter, it may be observed at this point that in treating a cotton of comparatively good grade containing only a negligible quantity of foreign matter, or in mixing two or more different grades of cotton, an imperforate casing similar to the casing 18 may be substituted for the screen 13. Either the screen 13 or the casing 18 may readily be removed by withdrawing the bolt 17 and thus allowing

the pipe to fall, and permitting the curved angle bars 14 to swing outwardly about their pivotal points 15.

By making one of the two shafts 36 adjustable to or from the other shaft, it is made possible for the lower end of one of the traveling aprons to yield in case it is necessary for a mass of cotton larger than usual to pass between the two aprons.

The invention is presented as including all such modifications and changes as properly come within the scope of the following claims.

What I claim is:

1. In a device of the character described, the combination with a gin saw cylinder and a brush cylinder mounted in the usual coöperative relation, of a pair of saw cylinders having a comparatively small diameter mounted above the gin saw cylinder and spaced horizontally from each other, means for subjecting said cylinders to a longitudinal reciprocating motion, a hopper mounted above the last named two cylinders and adapted to discharge material between the same, and means for communicating rotation to the saw cylinder, the brush cylinder, and the two saw cylinders of small diameter.

2. In a device of the character described, the combination with a gin saw cylinder and a brush cylinder mounted in the usual coöperative relation, of a pair of saw cylinders having a comparatively small diameter spaced vertically above the gin saw cylinder and horizontally from each other, means for communicating a longitudinal reciprocating motion to the last named two saw cylinders, a hopper mounted above said cylinder and adapted to discharge material between the same, the inclined side walls of said hopper being formed by downwardly traveling aprons, means for maintaining the travel of said aprons, and means for communicating rotation to the gin saw cylinder, the brush cylinder, and the two saw cylinders of comparatively small diameter.

3. In a device of the character described, the combination with a gin saw cylinder and a brush cylinder mounted in the usual coöperative relation, of a pair of saw cylinders having a comparatively small diameter mounted above the gin saw cylinder and spaced horizontally from each other, means for subjecting said small cylinders to a longitudinal reciprocating motion, means for communicating opposite rotation to the saw cylinders of small diameter, and means for communicating rotation to the brush cylinder and large saw cylinder.

4. In a device of the character described, the combination with a gin saw cylinder and a brush cylinder mounted in the usual coöperative relation, of a pair of feed cylinders having a comparatively small diameter

mounted above the gin saw cylinder and adapted to feed material downwardly between the adjacent portions, means for subjecting said feed cylinders to longitudinal reciprocating motion, a means for communicating rotation to a large saw cylinder, the small feed cylinder and the brush cylinder.

5. In a device of the character described, the combination with a gin saw cylinder and 10 a brush cylinder mounted in the usual cooperative relation, of a pair of saw cylinders having a comparatively small diameter spaced vertically above the gin saw cylinder and horizontally from each other, means 15 for communicating a longitudinal reciprocating motion to the last named two saw cylinders, a hopper mounted above said cylinder and adapted to discharge material between the same, the inclined side walls of 20 said hopper being formed by downwardly traveling aprons, means for maintaining the travel of said aprons, means resiliently supporting the lower end of one of said aprons in its proper spaced relation to the lower 25 end of the other apron, said means serving to permit an increased spacing of the lower apron extremities during the passage of an abnormally large mass of material between the same, and means for communicating rotation to the gin saw cylinder, the brush 30 cylinder, and the two saw cylinders of comparatively small diameter.

6. In a cotton cleaning mechanism, the combination with a toothed rotating axially 35 stationary cylinder, of bat-feeding devices adjacent the cylinder which move the bat axially thereof.

7. In a cotton cleaning mechanism, the combination with the relatively large 40 toothed rotating axially stationary cylinder, of the relatively small toothed bat-feeding cylinders adjacent the larger cylinder which compress the bat and move the front edge portion thereof axially of the cylinder.

45 8. In a cotton cleaning mechanism, the combination of the main rotating toothed cylinder, means for feeding cotton toward the cylinder, means for forming a bat of the cotton, and bat-feeding devices which reciprocate axially of the cylinder.

50 9. In a cotton cleaning machine, the combination of an initial cotton receptacle, means for forming a relatively compact cotton bat, means for engaging with the front 55 end of the bat and disintegrating it, and bat-engaging devices which move the bat bodily laterally relatively to the disintegrating devices.

10. In a cotton cleaning machine, the combination of the rotary toothed cylinder, the 60 initial receptacle for the cotton, means for forming a bat of the cotton and advancing it toward the cylinder, and supplemental

means for reciprocating the bat axially of the cylinder.

65 11. In a cotton cleaning mechanism, the combination of a rotary toothed cylinder, an initial receptacle for the cotton, means for forming a bat therefrom, and means immediately adjacent the cylinder for reciprocating the bat axially of the cylinder and simultaneously compressing the front edge portion of the bat.

70 12. In a cotton cleaning mechanism, the combination of a rotary toothed cylinder, an initial receptacle for the cotton, means between said receptacle and the cylinder for forming a relatively wide thin compact bat and advancing the front edge thereof toward said cylinder, and devices for causing the 80 bat-feeding means to reciprocate the bat axially of the cylinder.

75 13. In a cotton cleaning machine, the combination of a rotating toothed saw cylinder, means for forming a cotton bat and compressing it, supplemental means adjacent the cylinder for further compressing the bat, and means for causing the bat to reciprocate 85 axially of the cylinder.

80 90 14. In a mechanism for cleaning and re-ginning cotton, the combination of a rotating saw cylinder, a vertically arranged upwardly elongated hopper-like receptacle in which the cotton can be miscellaneous accumulated and through which it will tend 95 to move downward by gravity, said hopper having elongated flat walls formed of downwardly converging aprons adapted to compress the downward settling mass of cotton into a relatively compact bat, and having a 100 delivery throat directly over said saw cylinder, and a pair of opposed compacting rollers between the said cylinder and the said hopper throat, said rollers being arranged to receive said bat between them and 105 further compress it and being of relatively small diameter, whereby while gripping said bat they deliver its advancing edge directly to the teeth of the cylinder.

15. In a cotton re-ginning machine having 110 a vertically mounted hopper with two sides formed of converging traveling aprons, a pair of toothed feeding cylinders and a single toothed cylinder, the said pair of feeding cylinders being mounted above said single cylinder to feed cotton radially thereto and means for producing relative reciprocal movement between said single cylinder and said pair of feeding cylinders.

115 120 In testimony whereof I have signed my name to this specification in the presence of two subscribing witnesses.
